ADJUSTABLE BOOK RACK

Leonard Entin, Wayland, Mass., assignor to
Opus, Incorporated, Boston, Mass.

Filed Oct. 9, 1974, Ser. No. 513,456

Term of patent 14 years

Int. Cl. D6—04

U.S. Cl. D6—184

FIG. 1 is an isometric view of an adjustable book rack showing my new design;

FIG. 2 is a side elevation view thereof; and

FIG. 3 is an end view thereof, on an enlarged scale, with the vertical panel broken away for convenience of illustration.

I claim:

The ornamental design for an adjustable book rack, as shown and described.
